UNITED STATES PATENT OFFICE.

CHARLES L. HEISLER, OF SCHENECTADY, AND FREDERICK WILLIAM HEISLER, OF UTICA, NEW YORK.

GOVERNOR FOR CONTROLLING THE SPEED OF ENGINES AND MACHINERY.

1,099,364.

Specification of Letters Patent.

Patented June 9, 1914.

Application filed November 21, 1911. Serial No. 661,452.

To all whom it may concern:

Be it known that we, CHARLES LOUIS HEISLER, a citizen of the United States, and a resident of Schenectady, in the county of Schenectady and State of New York, and FREDERICK WILLIAM HEISLER, a citizen of the United States, resident of Utica, in the county of Oneida and State of New York, have invented certain new and useful Improvements in Governors for Controlling the Speed of Engines and Machinery, of which the following is a specification.

Our invention relates more particularly to governors arranged in an inclosing case and in the manner illustrated by the accompanying drawings, in which—

Figure 1 shows an exterior end view; Fig. 2 an exterior side view; Fig. 3 is a cross sectional side view, and Fig. 4 an end view in which the conical cover with its mechanism is removed to show the revolving semi-circular cheese weights shown in Fig. 5 and indicated by the numerals 1 and 1^a.

These semi-circular weights are of precisely the same construction and are each provided with a spring pocket 1^b and 1^c arranged to inclose a centrally and symmetrically located spring 2 as indicated by the dotted lines in Figs. 3 and 4. The weights are pivotally mounted upon the T head 12^a of the driving spindle 12 by means of the T-head pins 27 and 27^a forming pivotal supports that extend through the weights as shown. As usual the spring 2 opposes the centrifugal and inertia action of the fly weights, but will not always hold them in symmetrical relation to the rotating axis located in the axis of the driving spindle 12, therefore, it is necessary to provide two parallel links 25 and 25^a that are placed equally distant from and parallel with the T-head 12^a and pivotally mounted upon pins 26, 26^a, 26^b and 26^c placed in parallel lines, passing these pins and equally distant from the spindle axis as shown in Fig. 5, which also shows that the several members of this construction are always in perfect rotating balance and because the spring resistance is in a line that passes through the rotating axis and through the center of gravity of the two semi-circular inertia fly weights, therefore, a minimum frictional pressure is put upon the pins 27

and 27^a regardless of the mass and speed of the governor weights. The adjustment 55 of the spring is made in the usual manner by means of adjusting nuts reached through a suitable opening 35 in the inclosing case 11. It will be noticed that the parallel lines containing the pivotal points 26, 26^a, 26^b and 26^c 60 are placed at an angle with the line of parting 37 between the two weights 1 and 1^a. Furthermore, these parting lines remain parallel with each other as the weights separate, as shown in Fig. 5. The construction 65 and arrangement of these weights and their accessories evidently give the greatest possible mass in a minimum space combined with the greatest simplicity.

The transmission of the movement of the 70 weights to the rotating piston rod 5 is accomplished by means of the links 3 and 3^a pivotally connected with the pins 26 and 26^a, and the crosshead 4 that slidably engages with the T-head formed on the rotating piston rod 5. From Fig. 5 it is evident that the pins 26 and 26^a approach each other when the weights separate, thereby causing the piston rod to move to the right in Fig. 3 75 against the resistance of the liquid contained in the dash-pot cylinder 6 the flow of the liquid being adjusted by the set-screw plug 28 arranged in the passage 29 between the opposite sides of the rotating and reciprocating piston 6^a. At the right end of the 80 piston rod 5 a ball thrust bearing 7 is arranged to transmit the thrust from the governor weights to the elbow lever 8 and against the resistance of the adjusting spring 9, whose tension is changed by means 85 of the screw 24. Evidently the rotation of the dash pot piston and rod eliminates from these members and the stuffing boxes all frictional resistance to reciprocation regardless of any carelessness which may have 90 caused them to be abnormally tight. This arrangement produces an extremely stable 95 and sensitive governor.

As shown, the mechanism is inclosed in an oil-tight case, with the dash pot formed 100 therein, and the oil leakage from the dash pot gives ample lubrication for the inclosed moving parts including the spindle 12, thereby forming a complete self-oiling governor 105 with a frictionless dash pot.

When driven by a chain or belt, it is de-

sirable to use the weighted arm and pulley 14 and 15 pivotally mounted upon the bearing 31^a formed on an extension of the case 11 and inclosed by the sleeve 31, which rigidly connects the arm 15 with the lever 16 shown in Fig. 1. A slotted link 17 gives sufficient freedom to the lever 15 to compensate for usual variations in the belt deflections. In case of a broken belt, the excessive movement of the arm 15 would evidently cause the controlling rod 32 to be moved to the left and close the engine valve to which the controlling rod may be attached.

15 When the governor is to have sole control of the engine, then the lever 22, Fig. 1, remains stationary in any preadjusted position. However, when the movement or position of an accumulator—as in a hydraulic pumping engine system—is to stop or speed the engine, then the lever 22 is connected to the accumulator, and the governor elbow lever 8 is attached by means of the link 23 to the middle of the floating lever 20, as shown. Evidently the relative positions of these levers and fulcrums may be changed to suit local conditions so long as they fulfil their functions in the manner described.

20 The spring latch 19, Fig. 1, is for the purpose of causing the controlling rod 32 to move with the arm 20 excepting when the belt breaks and causes the rod to be moved to the extreme left for closing the engine valves.

25 As shown, the case 11 is covered by a conical hood or lid 10 that contains the dash pot 6 and a bracket having a pivotal bearing 30 for supporting the elbow lever 8. This lever lies normally in a horizontal plane, which also contains the driving spindle 12 with its pulley 14. The lower pivotal bracket 36 supports the levers 21 and 22 and is secured to the pedestal formed on the case 11.

30 Claims:

1. In a governor, the combination of means for producing centrifugal force, a dash-pot comprising a stationary member, a combined rotative and reciprocating member engaging therewith, one of said members being of cylindrical form and inclosing the other and slidingly engages therewith, for the purpose of minimizing friction.

2. In a governor, the combination of means for producing centrifugal force, means for producing resistance opposing said force, means adapted to resist sudden and undesirable acting of said governor and which comprises a retarding fluid, a piston having a contact surface, means for coupling it to the governor, a cylinder having a contact surface adapted to engage the piston, and means adapted to cause the surfaces in contact between said piston, and

the cylinder, to have a motion parallel with the axis thereof, and another about said axis, for the purpose of minimizing friction.

3. In a governor, the combination of means for producing centrifugal force, a spring resistance opposing said force, a dash-pot to resist sudden and undesirable action of said governor, said dash-pot comprising an internal piston having a retarding fluid on each side thereof, a piston rod secured thereto and actuated reciprocatively and rotatively by said governor, and adapted to transmit a combined reciprocative and rotative motion to said piston for the purpose of minimizing friction.

4. In a governor, the combination of means for producing centrifugal force, a spring resistance opposing said force, a system of levers for coupling said governor to an engine or other machinery, a dash-pot to resist sudden and undesirable action of said governor, said dash-pot comprising an internal piston having a retarding fluid on each side thereof, a piston rod secured thereto and actuated reciprocatively and rotatively by said governor, in combination with a thrust ball bearing adapted to transmit the reciprocating movement from this governing arrangement to the lever system connecting the governor to an engine or other mechanism.

5. In a governor consisting of a rotative shaft having a head with pivotal pins, semi-circular weights mounted upon said pins and placed symmetrical with respect to each other and the shaft, and with their straight sides adjacent to each other, being held in this position by a resisting coil spring placed within pockets formed in the semi-circular weights and directly across the axis of said shaft, and means for transmitting motion from these weights to a controlling rod.

6. In a governor, comprising a rotative shaft having a head with pivotal pins formed thereon, inertia fly weights pivotally mounted upon said pins and having their center of gravity disposed at some distance therefrom, and symmetrical with respect to each other and the shaft, a resisting spring coupled to the inertia fly weights and disposed directly across the axis of said shaft, a controlling rod, means for transmitting motion thereto from the weights; and links, disposed parallel one to the other and coupled to said weights which are adapted to swing in a plane perpendicular to the shaft.

7. In a governor, comprising a rotative shaft having a head with pivotal pins formed thereon, inertia fly weights pivotally mounted upon said pins and having their center of gravity disposed at some distance therefrom, and symmetrical with respect to each other and the shaft; a resisting spring

coupled to the inertia fly weights and disposed directly across the axis of said shaft, a controlling rod, means for transmitting motion thereto from the weights; and a plurality of links coupled to said weights and disposed, one parallel to the other and to a line passing through the pins on said head.

8. In a governor, comprising a rotative shaft having a head with pivotal pins formed thereon, inertia fly weights pivotally mounted upon said pins and having their center of gravity disposed at some distance therefrom, and symmetrical with respect to each other and the shaft, a resisting spring coupled to the inertia fly weights, a controlling rod, means for transmitting motion thereto from the weights which are adapted to swing in a plane perpendicular to the shaft, a plurality of pivotal bearings, formed on each weight and disposed in the intersections of lines parallel one to the other and with lines parallel to a line passing through pivotal pins formed on the head.

25 9. In a governor, comprising a rotative shaft having a head with pivotal pins formed thereon, inertia fly weights pivotally mounted upon said pins and having their center of gravity disposed at some distance therefrom, and symmetrical with respect to each other and the shaft, and with their sides adjacent to each other, being held in this position by a resisting coil spring disposed directly across the axis of the shaft, 30 a controlling rod, means for transmitting motion thereto from the weights, parallel links coupling said weights, by means of pivotal connections disposed in lines parallel to each other and to one which passes 35 through the pivotal pins, said links being

made parallel with the head and located equally distant therefrom.

10. In a governor, the combination of means for producing centrifugal force, a spring resistance opposing said force, a dash-pot to resist sudden and undesirable action of said governor, said dash-pot comprises an internal piston having a retarding fluid on each side thereof, a piston rod secured thereto and actuated reciprocatively and rotatively by said governor, and adapted to transmit a combined reciprocal and rotative motion to said piston, a stuffing box disposed at each end of the dash-pot and adapted to engage with the piston rod which 55 extends through the dash-pot and projects from each end thereof.

11. In a governor, the combination of means for producing centrifugal force, a spring resistance opposing said force, a dash-pot to resist sudden and undesirable action of said governor, said dash-pot comprises an internal piston having a retarding fluid on each side thereof, a piston rod secured thereto and actuated reciprocatively and rotatively by said governor, and adapted to transmit a combined reciprocal and rotative motion to said piston, a stuffing box disposed at each end of the dash-pot and adapted to engage with the piston rod which 60 extends through the dash-pot and projects from each end thereof, links coupling one end of the rod to said weights, and means for coupling the opposite end of the rod to an engine or other mechanism.
